(57) **CLAIM**

The ornamental design for a pet drying machine, as shown and described.

DESCRIPTION

FIG. 1 is a perspective view of a first embodiment showing my new design;

FIG. 2 is another perspective view of the first embodiment showing my new design;

FIG. 3 is still another perspective view of the first embodiment showing my new design;

FIG. 4 is a front elevational view of the first embodiment;

FIG. 5 is a perspective view of a second embodiment showing my new design;

FIG. 6 is another perspective view of the second embodiment showing my new design;

FIG. 7 is still another perspective view of the second embodiment showing my new design; and,

FIG. 8 is a front elevational view of the second embodiment. The broken line matter throughout the drawings is not claimed.
